UNITED STATES PATENT OFFICE.

HUGH D. MACPHERSON, OF SUMMIT, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

Application filed December 31, 1919. Serial No. 348,611.

To all whom it may concern:

Be it known that I, HUGH D. MACPHERSON, a citizen of the United States, residing at Summit, in the county of Union, State of New Jersey, have invented certain new and useful Improvements in Telephone Systems, of which the following is a full, clear, concise, and exact description.

This invention relates to telephone systems and more particularly to such systems in which the signals for a plurality of trunk lines extending between widely separated stations are controlled over a single signaling path common to such trunk lines.

In systems of this character it has been proposed to employ at opposite ends of the signaling path, signal sending means for transmitting over the signaling path code signals individual to the different trunk lines and determined by the trunk line in signaling condition.

It is the object of this invention to provide improved means for determining and setting up the different code signals to be transmitted by the signal sending means, for sending the signals as soon as set up and for preventing the simultaneous setting up and transmitting of two code signals in the same direction.

The means provided by the present invention for attaining this object will be more readily understood by reference to the accompanying drawings in which Figs. 1 to 4, when arranged with Fig. 2 below Fig. 1, Fig. 3 to the right of Fig. 1, and Fig. 4 below Fig. 3, are a diagrammatic representation of a telephone system embodying the present invention.

The equipment shown in Figs. 1 and 2 is located at an office X, that to the left of the dotted line in Fig. 3 and that in Fig. 4 is located at an office Y, while the apparatus to the right of the dotted line in Fig. 3 is located at an office Z. A telephone line G is also shown terminating in a jack 117 at office Z. A single trunk line L² terminating in a jack 21 at office X and a plug 100 at office Y is shown, but in practice many such lines would be associated with a single signaling path common to a group of lines. One toll switching trunk H terminating in a jack 101 and a plug 129 for extending connections from office Y to line G is shown, but it is to be understood that any suitable

number might be used. Only that end of a cord circuit F which cooperates with the trunk lines L is shown, as the other end of this cord circuit may be of any design suitable for cooperating with subscribers or local trunk lines terminating in the office X.

Below the horizontal dotted line in Fig. 1 are shown sets of relays J, K and M for determining the code signal to be set up for each individual line belonging to a group. One such set of relays is provided for each line in a group, but as their circuits are identical with the exception of the conductors to which the right-hand contacts of the relays M are tied, only the sets individual to lines L¹, L², L³ and L³¹ have been shown. From each set of relays three conductors A, B and C extend to apparatus individual to the line which controls these relays, only those extending to line L² being shown in full, since the other conductors A, B and C extend to corresponding points in their respective lines.

The J, K and M relays together with the relays shown in Fig. 2 constitute the impulse storing and sending equipment designated SE. In Fig. 4 is shown the impulse receiving equipment RE', comprising impulse receiving relays at the left of the drawing and pyramid line selecting relays at the right of the drawing. The contacts of relays 190' to 197' are connected to conductors D' individual to the lines of the group, but as they all lead to corresponding points in their respective line equipment, only conductor D' individual to line L² is shown in full. Impulse receiving equipment is provided at office X, but as it is identical with that at office Y, it has been indicated by the dotted rectangle RE in the lower right-hand corner of Fig. 2. Similarly impulse sending equipment identical with SE at office X is provided at office Y and is indicated by the dotted rectangle SE' in the lower left-hand corner of Fig. 4. Like apparatus at offices X and Y is numbered alike, without primes at office X, with primes at office Y. In order that signals may be sent in opposite directions simultaneously duplex equipment comprising differentially wound polarized relays 40 and 40' and artificial lines AL is connected to the ends of the common signaling conductor P at offices X and Y respectively.

It is to be noted that all slow operating and releasing relays employed are conventionally illustrated as such by arrows intersecting the armatures of said relays and pointing in the direction in which said armatures are slow to move.

It is believed that the invention will now be understood from a consideration of the operation of the system which is as follows:

10 *Connection of cord circuit F with trunk line L².*

The operator at the office X desiring to establish a connection with the telephone line circuit G terminating at office Z, connection with which line must be established through office Y, communicates in the usual manner with the operator at office Y over an order wire circuit (not shown). The 15 operator at office X upon ascertaining from the operator at office Y that the trunk line circuit L² shall be used in completing the connection inserts the calling plug 20 of a link circuit F at office X into jack 21 of the 20 trunk line L². Relay 22 thereupon operates over a circuit extending from battery through lamp 23, the sleeve contacts of plug 20 and jack 21 and the winding of relay 22 to ground. However, the resistance of the 25 winding of relay 22 is sufficient to prevent the lighting of lamp 23. A circuit is thereupon established from battery through resistance 37, the winding and normal contact of relay 24, the alternate contact of 30 relay 22, and the normal contact of relay 28 to ground. Relay 24 operates due to the 35 current flowing through this circuit and locks over a circuit extending from battery through resistance 37 and the winding and middle alternate contact of relay 24 to ground. A circuit for relay 30 is also closed 40 through the right hand alternate contact and winding of relay 24, but relay 30, being marginal, does not operate in series with 45 relay 24. A circuit is also formed from battery through the right-hand normal contact of relay J¹, the right-hand normal contact of relay J², the left-hand normal contact of relay J², and winding thereof, conductor A², the right-hand normal contact of 50 relay 30, the alternate contact of relay 22, and the normal contact of relay 28 to ground. Relay J² operates and locks over a circuit extending from battery through the 55 left-hand alternate contact and winding of relay J², conductor A², the right-hand normal contact of relay 30, the alternate contact of relay 22 and the normal contact of relay 28 to ground. The opening of the 60 right-hand normal contact of relay J² interrupts the continuity of the battery supply circuit for operating the J relays associated with the succeeding lines of the system. The closure of the right-hand alternate contact of relay J² operates relay K² over a cir-

cuit extending from battery through the winding of relay K², the right-hand alternate contact of relay J², the middle normal contacts, in series, of the intervening relays between the relay J² and the relay J³¹ to the 70 right-hand normal contact of relay J³¹ to ground. The opening of the middle normal contact of relay J² interrupts the continuity of the conductor leading to the preceding K relays. Relay M² thereupon operates over a circuit extending from battery through the winding of relay M², the middle contact of relay K², and the normal contact of relay 38 to ground. The closure of 75 the left-hand contact of relay M² in operating prepares a circuit for relay 50 and the closure of the right-hand alternate contact of relay M² completes a circuit extending from battery through the winding of relay 41, the winding of relay 45, and the right-hand alternate contact of relay M² to ground. The closure of the right-hand contact of relay 41 causes the operation of relay 80 85 43 over a circuit extending from battery through the winding of relay 43, the right-hand contact of relay 41, the upper normal contact of relay 52 and the upper normal contact of relay 51 to ground. The opening of the normal contact of relay 43 removes the ground connection from the conductor 85 leading to the polar relay 40, included in the common signaling path P and the closure of the right-hand alternate contact of relay 43, connects such common signaling path to an armature of relay 45. The closure 90 of the left-hand alternate contact of relay 43 completes a circuit for relay 42, which extends from battery through the winding of relay 42, the left-hand contact of relay 41, and the left-hand contact of relay 43, to ground. Relay 47 thereupon operates over a circuit extending from battery through the winding of relay 47, the right-hand alternate contact of relay 45, and the contact of relay 42 to ground. However, 95 prior to the operation of relay 47, the positive terminal of the 120 volt source of current is connected to the common signaling path P, for a predetermined length of time, through the normal contact of relay 47, the left-hand alternate contact of relay 45, and the right-hand alternate contact of relay 43. Relay 47 in opening its normal contact disables this circuit and completes a circuit 100 which extends from battery through the winding of relay 46, the upper alternate contact of relay 47, the right-hand alternate contact of relay 45, and the contact of relay 42 to ground. The closure of the left-hand alternate contact of relay 46 completes a circuit 105 for relay 58, extending from battery through the winding of relay 58, the right-hand normal contact of relay 55, and the left-hand alternate contact of relay 46, to ground. However, after the operation of 110 115 120 125 130

the right-hand alternate contact of relay 46, the lower alternate contact of relay 47, the left-hand alternate contact of relay 45, and the right-hand alternate contact of relay 43. Relay 43 releases upon the opening of the upper normal contact of relay 52, thus causing the release of relay 42 which in turn removes the ground connection from the circuit including the winding of relay 47 and the latter relay in releasing in response to this operation causes the release of relays 46, 58, 56, 68, 66, 78, 76, 88, 86 in sequence, and the release of relay 43 disconnects the signal initiating relays from association with the common signaling path P and restores the normal ground connection thereto. The closure of the upper alternate contact of relay 52 completes a circuit for relays 39 and 38, the circuit for relay 38 extending from battery through the winding of relay 38, the contact of relay 39, the upper alternate contact of relay 52 and the upper normal contact of relay 51 to ground; while the circuit for relay 39 extends from battery through the winding of relay 39, the upper alternate contact of relay 52, and the upper normal contact of relay 51, to ground. Relay 38 operates over the circuit traced therefor prior to the operation of relay 39, which is slightly slow in opening its contact, and locks over a circuit established from battery through the winding and left-hand alternate contact of relay 38 to the right-hand contact of relay K² where it joins the circuit previously traced for the latter relay. A circuit is also completed from battery through the winding and the left-hand normal contact of relay 30, lead B², the left-hand alternate contact of relay K², and the right-hand alternate contact of relay 38 to ground. Relay 24 is short-circuited and released by the ground on conductor B², but again energizes and locks over the circuits previously traced therefor when said ground is removed. It will be noted that while conductor B² remains grounded, relay 24, upon operating, is immediately shunted and released so that such relay is intermittently operated until the ground is removed from such conductor. However, this condition is only momentary while the impulse is being transmitted and produces no material effect upon the system, since relay 22 remains operated. Relay 30 responds to the current flowing through the circuit and in operating, locks over a circuit extending from battery through the winding and left-hand alternate contact of relay 30, the alternate contact of relay 22 and the normal contact of relay 28, to ground. The opening of the right-hand normal contact of relay 30 causes the release of relay J² which in turn releases relay K² and relay M² in sequence, the release of relay M² releasing relays 45 and 41. The

release of relay J² opens the locking circuit of relay 38 to deenergize this relay and thereby remove ground from the conductor B² whereupon relay 24 again energizes and locks. Relay 52 releases upon the release of relay 86 so that all apparatus in connection with the signal restoring and signal sending equipment at office X is restored to normal except relays 22, 24 and 30 which remain in an operated condition. 75

The first signal transmitted over the common signaling path P in response to the operation of relay 45, causes relay 40' at office Y to close its upper contact, thereby completing a circuit from battery through the normal contact of relay 134', the right-hand normal contact and left-hand winding of relay 132', the right-hand normal contact of relay 131' and the upper contact of relay 40' to ground. Relay 132' operates and relay 131' then operates over a circuit extending from battery through the normal contact of relay 134', the windings of relay 132' in series, the left-hand alternate contact of such relay and the winding of relay 131' to ground. In operating relay 132' opens its normal contact, removing the normal short-circuit existing around the right-hand winding of such relay, thus reducing the current flow through the windings of such relays to a predetermined amount thus preventing injurious effects which might result from a continued flow of the original operating current. Relays 190', to 197', inclusive, thereupon operate over a circuit extending from battery through the windings of such relays in series and the right-hand alternate contact of relay 132' to ground. The second impulse received over the common signaling path P being of the opposite polarity causes relay 40' to close its lower contact whereupon relay 140' operates over a circuit extending from battery through the normal contact of relay 134', the left-hand contact and right-hand winding of relay 140', the left-hand normal contact of relay 141', the left-hand alternate contact of relay 131', and the lower contact of relay 40' to ground. The opening of the normal contact of relay 140', as in the case of relay 132', removes the normal short circuit from the left-hand winding of such relay and the closure of the right-hand contact of relay 140' causes the operation of relay 141' over a circuit extending from the circuit for relay 140', through the right-hand contact thereof and the winding of relay 141' to ground. The next impulse received over the common signaling path causes relay 40' to close its lower contact whereupon relay 150' operates over a circuit extending from battery through the contact of relay 134', the left-hand contact and the right-hand winding of relay 150', the left-hand normal contact of relay 151', the left-hand alternate contact of relay 141', the 110 115 120 125 130

left-hand alternate contact of relay 131' and the lower contact of relay 40' to ground. Relay 150' in operating removes the short circuit existing around its left-hand winding and causes the operation of relay 151' in a manner similar to that described for relays 140' and 141'. The succeeding impulse transmitted, being of the same polarity, causes relay 40' to again close its lower contact, thereby causing the operation of relay 160' over a circuit extending from battery through the contact of relay 134', the left-hand contact and right-hand winding of relay 160', the left-hand normal contact of relay 161', the left-hand alternate contacts of relays 151', 141', and 131' in series, and the lower contact of relay 40' to ground. As in the case of relays 150' and 151', the operation of relay 160' removes the normal short circuit existing around its left-hand winding and causes the operation of relay 161'. The succeeding impulse transmitted over the common signaling path being of a similar polarity, causes relay 40' to again close its lower contact, whereupon relay 170' operates over a circuit extending from battery through the contact of relay 134', the left-hand contact and right-hand winding of relay 170', the left-hand normal contact of relay 171', the right-hand alternate contacts of relays 161', 151', 141', and 131' and the lower contacts of relay 40' to ground. As in the case of relay 140' and 141', relay 170' in operating removes the normal short circuit existing around its left-hand winding and causes the operation of relay 171'. The next impulse being of a similar polarity again causes relay 40' to close its lower contact whereupon relay 180' operates over a circuit extending from battery through the contact of relay 134', the normal contact and right-hand winding of relay 180', the left-hand alternate contacts of relays 171', 161', 151', 141', and 131' in series, and the lower contact of relay 40' to ground. As in the previous instances, relay 180', in operating, removes the normal short circuit existing around its left-hand winding and causes the operation of relay 181'. The closure of the left-hand alternate contact of relay 180' also completes a circuit extending from the positive terminal of battery through the contact and winding of relay 133', the left-hand alternate contact of relay 180', the normal contact of relay 153', the lower normal contact of relay 163', the lower normal contact of relay 174', the lower normal contact of relay 186', and the lower alternate contact of relay 197', where it connects with receiving conductor D'2 and extends through the left-hand winding of relay 116 to ground. Relay 116 is thereby operated and locks over a circuit extending from battery through its right-hand alter-

uate contact and right-hand winding to ground. In closing its left-hand alternate contact, relay 116 causes the lighting of guard lamp 138 over a circuit extending from battery through the lamp 138, the normal contact of relay 103, and the left-hand alternate contact of relay 116 to ground, as well as causes the operation of transfer relay 115 over an obvious circuit to connect conductor D'2 with the right-hand winding of relay 114 through the contact of relay 115, but due to the cessation of the impulse, no effect is produced upon relay 114. Relay 133' in operating removes the normal short circuit existing around resistance 136' to reduce the current flowing through the signal conductor to a safe value for a continued flow, and relay 181' in operating, causes the operation of slow-operating relay 134', thereby removing the battery connection from the circuits over which relays 131', 132', 140', 141', 150', 151', 160', 161', 170', 171', 180' and 181' are held energized, thereby releasing such relays and by the release of relay 181' causing the release of relays 133' and 134' to restore the impulse-distributing apparatus to normal. The opening of the right-hand alternate contact of relay 132' releases relays 190' to 197' inclusive, thereby restoring the pyramid selecting relays to normal.

Connection of toll switching trunk H with line G.

At the time the operator at office Y designates the trunk line with which operator at office X connected the cord circuit F, the operator at office Y also communicates with the office Z over an order wire circuit (not shown), advising the operator thereat the number of the line with which connection is desired, whereupon the operator at the office Z designates the toll switching trunk circuit over which the connection should be established from office Y to office Z. Assuming that the toll switching trunk circuit H is the one designated, the operator at office Z thereupon inserts the plug 129 of the trunk circuit H into the jack 117 of the line circuit G. Sleeve relay 125 and cut-off relay 118 operate over a circuit extending from battery through the winding of relay 125, the sleeve contacts of plug 129 and jack 117, and the winding relay 118 to ground. The operation of the cut-off relay 118 disconnects the line relay 119 from the line conductors in the usual manner. The operation of the sleeve relay 125 causes the lighting of supervisory lamp 124 over a circuit extending from battery through the lamp 124, the lower alternate contact of relay 125, the resistance 123, and the normal contact of relay 121 to ground.

Connection of trunk line circuit L^2 with toll switching trunk circuit H .

The operator at office Y observing the lighted condition of the lamp 138 inserts plug 100 of the trunk line L^2 into the jack 101 of the toll switching trunk circuit H . Relay 102 thereupon operates over a circuit extending from battery through the winding of relay 102 and the sleeve contacts of plug 100 and jack 101, to ground. The closure of the contact of relay 102 causes the operation of relay 103 over a circuit extending from battery through the winding of relay 103, and the contact of relay 102, to ground. The closure of the upper alternate contact of relay 103 establishes the continuity of the tip conductor of the trunk line circuit L^2 , which conductor is normally discontinuous for the purpose of making the usual busy test. The opening of the lower normal contact of relay 103 causes the extinguishment of guard lamp 138. A circuit is thereupon completed extending from battery through the left-hand winding of relay 121, the left-hand normal contact of relay 122, the tip contacts of jack 101 and plug 100, the upper alternate contact of relay 103, the upper normal contact of relay 104, the winding of relay 105, the middle normal contact of relay 104, the ring contacts of plug 100 and jack 101, the right-hand normal contact of relay 122, and the right-hand winding of relay 121 to ground. Supervisory relays 105 and 121 are operated due to this circuit. The operation of supervisory relay 121 extinguishes supervisory lamp 124 and the operation of relay 105 causes the operation of relay 106 over a circuit extending from battery through the winding of relay 106, and the alternate contact of relay 105 to ground. Relay 108 also operates over a circuit extending from battery through resistance 143, the winding and normal contact of relay 108, the contact of relay 107, and the alternate contact of relay 105 to ground. Although a circuit is also completed at this time for relay 107, such relay does not operate due to its slow operating nature, until after relay 108 has operated. Relay 108 in operating locks over a circuit extending from battery through resistance 143, the winding and right-hand alternate contact of relay 108, to ground. The closure of the left-hand alternate contact of relay 108 causes the operation of relay 109 over a circuit extending from battery through resistance 110, the winding and normal contact of relay 109 and the left-hand alternate contact of relay 108 to ground. Relay 109 locks over a circuit extending from battery through resistance 110 and the winding and left-hand alternate contact of relay 109 to ground. The closure 65 of the left-hand alternate contact of relay

108 also connects ground with conductor A^2 leading to the relay J^2 of the sending equipment SE' at office Y to cause the series of operations of the relays of such sending equipment corresponding to those previously described, for the relays of the sending equipment at office X caused by the grounding of conductor A^2 following the insertion of the plug 20 of the link circuit F into the jack 21 thereat. These impulses correspond in arrangement and character to those previously transmitted and select the line L^2 at the office X in the same manner that line L^2 was selected at the office Y. The impulses are received by the receiving equipment RE at office X which equipment corresponds with the receiving equipment at office Y and the last impulse upon being transmitted over the receiving conductor D^2 at office X causes the operation of relay 32 over a circuit including the right-hand winding of such relay. A circuit is thereupon completed from battery through the supervisory lamp 23 of the link circuit F, the sleeve contacts of plug 20 and jack 21, resistance 54, the right-hand alternate contact of relay 30, the left-hand alternate contact of relay 32, and the right-hand normal contact of relay 34 to ground. Due to the parallel relation of resistance 54 and the winding of relay 22, the amount of current flowing through this circuit is sufficient to cause the lighting of the lamp 23 to indicate to the operator at office X that the plug 100 has been inserted in the jack 101. However, insufficient current is diverted from relay 22 to cause its release at this time. Upon the grounding of the lead B^2 of the sending equipment SE' at office Y occurring in the sequence described for the grounding of lead B^2 at office X, relay 108 releases due to the shunting of the winding thereof by the resistance 143. Thus ground is removed from the lead A^2 of the sending equipment SE' in a manner similar to that described in connection with the relay 30 at office X. The sending equipment SE' thereupon is restored to its normal condition and is capable of being used in connection with any other line controlled thereby.

The operator at office X actuates the ringing key.

The operator at office X, upon observing the lighted condition of the supervisory lamp 23, actuates ringing key 60 associated with line circuit F, thereby causing the operation of the ringing response relay 28 over a circuit established from the source of alternating current, through the lower alternate contact of ringing key 60, through the ring contacts of plug 20 and jack 21, the winding of relay 28, condenser 29, the tip contacts of jack 21 and plug 20 and the upper alternate contact of ringing key 60 to ground.

The closure of the alternate contact of ringing response relay 28 causes the operation of relays 26 and 27 over obvious circuits, the operation of relay 27 causing the short-circuiting of the windings of the repeating coil thereby effectually preventing the transmission of ringing current over the conductors of line L^2 to the distant station. The opening of the normal contact of relay 26 interrupts the locking circuit of relay 30 to release the same but relay 24 remains operated over its locking circuit. Relay 30 in opening its right hand alternate contact interrupts the circuit for supervisory lamp 23 to extinguish this lamp, to inform the operator that the signal sending apparatus is functioning. When the signal has been sent relay 30 is operated as before to again complete the shunt of relay 22 through resistance 54 to light supervisory lamp 23. Relay 26, in operating, connects ground to lead A^2 through the alternate contact of relay 26, the alternate contact of relay 22, and the right-hand normal contact of relay 30. Thereupon the same series of operations follow as described in connection with the operation of relay 24 in connection with the initiation of the call. Relays J^2 , K^2 , M^2 and the other associated relays function in exactly the same manner as previously described, to transmit over the common signaling path P a similar set of impulses which are received by the relay 40' and cause the signal distributing and pyramid selecting relays at office Y to again select the conductor D^2 associated with the line L^2 at office Y . Following the selection of the line, the last impulse of the series is received over the line conductor D^2 and flows through the contact of relay 115 and right-hand winding of relay 114 to ground causing the operation of relay 114. Although this impulse also flows through the left-hand winding of relay 116, no effect is produced thereby since it produces magnetic flux in the same direction as that produced by the current flowing through the locking circuit of relay 116. Relay 114 thereupon locks over a circuit extending from battery through the left-hand winding and right-hand alternate contact of relay 114, and the lower normal contact of relay 104 to ground. Slow release relay 113 thereupon operates over an obvious circuit causing the subsequent operation of relay 111 over an obvious circuit and of relay 104 over a circuit extending from battery through the winding of relay 104 and the contact of relay 113 to ground. The closure of the contact of relay 111 maintains relays 106 and 107 in an operated condition independently of supervisory relay 105 which releases upon the opening of the upper and middle normal contacts of relay 104. The opening of the lower normal contact of relay 104 releases relay 114 and during its operated period, relay 104 completes a temporary circuit extending from the source of alternating current through the lower alternate contact of relay 104, the ring contacts of plug 100 and jack 101, the winding of relay 120, condenser 128, the tip contacts of jack 101 and plug 100, the upper alternate contact of relay 103 and the upper alternate contact of relay 104 to ground. Relay 120 in operating, causes the operation of relays 122 and ringing relay 127 over a circuit extending from battery through the left-hand winding of relay 122, the winding of relay 127, and the contact of relay 120 to ground. Relay 122 in operating disconnects relay 121 from the talking conductors of the toll switching trunk H during the time that ringing current is connected therewith and by the closure of its left-hand alternate contact prior to the opening of its left-hand normal contact maintains relay 121 operated over a circuit from battery through the left-hand winding of relay 121 and the left-hand alternate contact of relay 122 to ground. The operation of relay 127 causes the operation of the subscriber's bell at the station G over a circuit extending from the source of alternating current through the upper alternate contact of relay 127, the ring contacts of plug 129 and jack 117, the winding of the vibrating bell at the station G , the tip contacts of jack 117 and plug 129, the upper alternate contact of relay 125, and the lower alternate contact of relay 127 to ground. Upon the deenergization of relay 104, the ringing current is disconnected from the conductors of line L^2 leading to the toll switching trunk H causing the release of relays 120, 127 and 122 in sequence, the release of the latter relay reconnecting relay 121 to its original operating circuit so that relay 121 is maintained operated and relay 105 reoperates. The closure of the contact of relay 105 maintains relays 106 and 107 operated after the complete release of relay 111.

Operator at Office X restores ringing key.

Upon the restoration of the ringing key to normal, relay 28 deenergizes causing the release of slow release relay 26 and of relay 27, the latter relay removing the short-circuits established around the windings of the repeating coil. Relay 28 closes its normal contact to maintain a locking circuit for relay 30 prior to the interruption of the circuit for this relay through the alternate contact of relay 26.

The receiver of the station on telephone line G is removed from the switchhook.

The subscriber at the station on the telephone line G in responding to the operation of the call bell thereat, removes the receiver

from the switchhook causing the operation of supervisory relay 126 over a circuit extending from battery through the winding of relay 126, upper normal contact of relay 127, the ring contacts of plug 129 and jack 117, over one conductor of the line circuit, the apparatus at the station thereon returning over the other conductor of the line circuit, the tip contacts of jack 117 and plug 129, the upper alternate contact of relay 125, and the lower normal contact of relay 127, to ground. Relay 122 operates in response to the operation of relay 126, the energizing circuit, therefor, being traced from battery through the left-hand winding of relay 122, the contact of relay 126, the right-hand winding of relay 122, and the alternate contact of relay 121 to ground. Relay 122 in operating disconnects relay 121 from the circuit including the supervisory relay 105 of the line circuit L^2 but relay 121 is maintained energized due to the completion of a circuit extending from battery through the left-hand winding of relay 121 and the alternate contact of relay 122 to ground. Relay 105 is deenergized due to the opening of its operating circuit, relay 111 being released, the opening of the alternate contact of relay 105 interrupts the circuit of relays 106 and 107 to deenergize these relays. The release of relay 107 completes a circuit from battery through resistance 143, the winding and normal contact of relay 108, the normal contact of relay 107, the normal contact of relay 105, the right-hand alternate contact of relay 109, the normal contact of relay 106 and the winding of relay 144 to ground. Relay 108 operates over this circuit and locks over a circuit extending from battery through resistance 143, the winding and right-hand alternate contact of relay 108 to ground. Relays 106 and 144 also operate over a circuit extending from battery through the winding of relay 106, the normal contact of relay 105, the right-hand alternate contact of relay 109, the normal contact of relay 106 and the winding of relay 144 to ground. Immediately upon the operation of relay 106, relays 144 and 106 lock over a circuit extending from battery through the winding of relay 106, the normal contact of relay 105, the right-hand alternate contact of relay 109, the alternate contact of relay 106, the right-hand alternate contact and winding of relay 144 to ground. Relay 107 being slow in operating does not operate prior to the operation of relay 108, but then operates over a circuit from battery through the winding of relay 107, the normal contact of relay 105 and thence in parallel with the circuit for relay 106 through the winding of relay 144 to ground. The closure of the middle contact of relay 144 connects ground to conductor C^2 leading to the sending equipment SE' , and the closure of the left-hand

alternate contact of relay 108 connects ground with the conductor A'^2 leading to the sending equipment SE' , as in the previous cases. The grounding of the conductor A'^2 causes the series of operations of the sending equipment apparatus, as previously described, to transmit the same arrangement of selecting impulses as previously transmitted upon the insertion of the plug 100 into the jack 101, but due to the fact that the conductor C'^2 is grounded, pole changing relay 50' is operated so that the operation of relay 86', in connection with the last selecting impulse, causes the operation of relay 51' instead of relay 52', as in the previous instances, and as a consequence, the positive terminal of the 120 volt source of current is temporarily connected to the signaling path through the lower normal contact of relay 51' and the left-hand alternate contact of relay 50', instead of the negative terminal of the 120 volt source of current being connected thereto through the lower normal contact of relay 52' and the left-hand normal contact of relay 50', as in the previous instances. As a result of this change in the connection for the last impulse, the current is reversed, so that upon being received at office X the upper contact of relay 40 is closed, which causes the operation of relay 182 of the receiving equipment RE by the means of current flowing through the normal contact of relay 134, the normal contact and left-hand winding of relay 182, instead of through the normal contact of relay 134, the normal contact and right-hand winding of relay 180, as in the previous cases. Thus in closing the right-hand alternate contact of relay 182, a circuit is completed whereby negative current is sent out over receiving conductor D^2 , through the contact and winding of relay 135, instead of positive current being sent out through the contact and winding of relay 133. The last impulse, therefore, traversing the conductor D^2 , flows through the right-hand winding of relay 32 in such a direction as to differentialize such relay and cause it to release its armatures. The opening of the right-hand contact of relay 32 causes the release of slow-releasing relay 33, which in turn causes the release of relays 35 and 36 in sequence. The opening of the left-hand alternate contact of relay 32 disables the branch circuit including the resistance 54, so that such resistance is no longer in parallel relation with the winding of relay 22, and as a consequence, lamp 23 is extinguished, thus notifying the operator at office X that the subscriber at the station on the line G has answered. As in the previous instances, upon storing the impulses in the sending equipment SE' , the conductor B'^2 is grounded, thereby causing the release of relays 108 and 109 by shunting the windings 130

of such relays through the associated resistances 143 and 110 respectively. The release of relay 108 removes the ground connection from the conductor A², and the release of relay 109 opens the locking circuit of relays 106, 107 and 144, thereby allowing such relays to return to normal.

10 *Receiver of the station on telephone line G is replaced upon the switchhook.*

At the conclusion of the conversation the subscriber at the station of the telephone line G restores the receiver to the switchhook, whereupon supervisory relay 126 de-energizes, opening the circuit of and releasing relay 122. The closure of the normal contacts of relay 122 restores relay 121 to its normal association with the talking conductors of the toll switching trunk H, whereupon relay 105 is operated, over the circuit previously traced, in series with relay 121. In response to the operation of relay 105, relay 108 is operated and locked as previously described in connection with the signal transmitted from office Y to office X upon the insertion of the plug 100 in the jack 101. As in the preceding instance also, the grounding of the conductor A² by the closure of the left-hand alternate contact of relay 108 initiates the series of operations of the sending equipment SE' to transmit the same series of selecting and signaling impulses, as in the former case. These impulses upon being received for the signaling path P cause the operation of relay 40 to transfer such impulses into the receiving equipment RE at office X to select the signaling conductor D² of the line L², and to transmit thereover an impulse of current of positive polarity causing the operation and locking of relay 32, as in the previous instance. Resistance 54 is again included in parallel with the winding of relay 22 to reduce the resistance in series with the supervisory lamp 23 causing the same to be illuminated. Relay 33 also operates upon the closure of the right-hand alternate contact of relay 32 and relay 32 locks over the circuit including its middle alternate contact and left-hand winding, as in the previous instance. Relays 35 and 36 also operate in sequence following the operation of relay 33, and the signaling conductor D² is connected to the left-hand winding of relay 34 through the left-hand alternate contact of relay 33.

55 *Operator at office X disconnects cord circuit F from trunk line circuit L².*

The operator at office X, upon observing the continued illumination of supervisory lamp 23, removes plug 20 from the jack 21 causing the release of relay 22. Relay 30 is released by the opening of the alternate contact of relay 22 and an operating circuit for relays J² and 31 is thereupon completed

from grounded battery through the right-hand normal contact of relay J¹, the right-hand normal contact of relay J², the left-hand normal contact and winding of said relay conductor A², the left-hand normal contact of relay 30, the normal contact of relay 22, the left-hand alternate contact of relay 24 and the winding of relay 31 to ground. The energization of relay J² in this circuit, as in the previous instances, causes the operation of relays K² and M². The operation of relay M², however, performs an additional function at this time which consists in completing a circuit extending from battery through the winding of relay 50, the left-hand contact of relay M², the conductor C² and the contact of relay 31 to ground. In response to the operation of the relay M² and the relays controlled thereby, the same series of selecting impulses is impressed upon the signaling path P, as in the case of the initiation of the call, but due to the operation of relay 50, the operation of relay 86 causes the operation of relay 51 instead of relay 52, so that the last or signaling impulse is transmitted from the positive terminal of the 120 volt source of current through the lower normal contact of relay 51 and the left-hand alternate contact of relay 50, instead of from the negative terminal of the 120 volt source of current through the lower normal contact of relay 52 and the left-hand normal contact of relay 50. When relay 38 operates in response to the operation of relay 51, it connects ground over the path previously traced to conductor B², shunting relay 24 through resistance 37. Relay 24 in opening its left-hand alternate contact opens the circuit for relays 31 and J², and relay J² in deenergizing restores the impulse sending and storing equipment at office X in the manner previously described.

The selecting impulses being received at office Y cause the relay 40' to initiate the same series of operations of the signal impulse distributing and pyramid-selecting relays at office Y as were described in connection with the initiation of the call, whereby the signaling conductor D² leading to the trunk line L² is selected. However, due to the reversed polarity of the signaling impulse following these selecting impulses, relay 182' operates instead of 180', the circuit for the former relay being traceable from battery through the normal contact of relay 134', the normal contact and left-hand winding of relay 182', the right-hand alternate contacts of relays 171', 161', 151', 141' and 131' in series and the upper contact of relay 40' to ground. As in the previously described case, the opening of the normal contact of relay 182' removes the normal short-circuit existing around the right-hand winding of relay 182' to reduce the current flowing through the circuit, and the closure of

the left-hand alternate contact of relay 182' causes the operation of relay 181' over a circuit extending from battery through the normal contact of relay 184', the windings 5 of relay 182' in series, the left-hand alternate contact thereof, and the winding of relay 181' to ground. The closure of the contact of relay 181' causes the operation of relay 184', as in the other case, to remove 10 the battery from the various signal impulse receiving relays, allowing them to return to normal. However, during the operation of relay 182' an impulse of negative polarity is connected with the signaling conductor 15 D² through the contact and winding of relay 135', the resistance 137' being included in circuit with the winding of relay 135' upon its operation for the purposes of protection, as previously outlined in connection 20 with relay 133'. This signaling impulse being of the opposite polarity with respect to the impulse causing the operation of relay 116, causes relay 116 to become differentialized when it flows through the left-hand 25 winding of such relay. Upon the release of relay 116 in response to this differentializing action, lamp 138 is lighted over a circuit extending from battery through the lamp 138, the lower alternate contact of relay 103 and 30 the normal contact of relay 116 to ground. Relay 115 is also released due to the opening of the left-hand alternate contact of relay 116. The operator at office Y, observing the lighted condition of supervisory lamp 138, 35 removes plug 100 from jack 101 of the toll switching trunk H, thereby interrupting the circuit for relays 105 and 121 to deenergize these relays. Relay 105 in closing its normal contact completes energizing circuits for re- 40 lays 108, 107, 106 and 144 in the same manner as was described when relay 105 was deenergized due to the removal of the receiver at station G from its switchhook by the answering of the called subscriber, and the con- 45 sequent series of impulses acts, as in that case to send an impulse of negative polarity through the right-hand winding of relay 32 at office X. This impulse causes magnetic flux in the opposite direction to that 50 caused by the locking winding of relay 32, so that this relay is deenergized. Relay 32 in opening its right-hand contact deenergizes relay 33, and consequently relays 35 and 36, so that all the equipment at office X 55 is now restored to normal. The operation of relay 38' at the end of this series of im- 60 pulses grounds conductor B² to shunt relays 108 and 109 through resistances 143 and 110 respectively, and relay 109 in opening its right-hand contact deenergizes relays 107, 106 and 144 so that all the apparatus at office Y is now completely restored. The release 65 of supervisory relay 121, due to the removal of plug 100 from jack 101, causes the illumination of supervisory lamp 124 over a cir-

cuit extending from battery through the lamp 124, the lower alternate contact of relay 125, the resistance 123 and the normal contact of relay 121 to ground. The operator at office Z, upon observing the lighted condition of the lamp 124, removes plug 129 from the jack 117, whereupon all apparatus associated with the line circuit G and the toll switching trunk H returns to normal. 70

75 *Subscriber at station on telephone line G recalls the operator at office X.*

Should the subscriber at the station on the telephone line G, after answering a call when connection is established between the toll cord circuit F and the telephone line G by way of the trunk line L² and the toll switching trunk H, wish to signal the operator at office X, this may be accomplished 80 by rapidly opening and closing the switchhook contacts at the station on the telephone line G. The first opening of the switchhook contact would cause the operation of relay 105 of the connected trunk line L² which will cause the same series of selecting and signaling impulses to be transmitted from office Y, as in the case when the called subscriber at the station on line G replaced his receiver on its switchhook at the termination of the conversation. The signaling impulse which 85 is received by the conductor D² causes the operation of relay 32, which in turn causes the operation of relays 33, 35 and 36, as in the previous case, thereby completing a shunted path through resistance 54 around 90 the winding of relay 22, as in the previous case, and causing the illumination of supervisory lamp 23. The first closure of the switchhook contacts would cause the deenergization of relay 105, but as relay 106 is 95 energized at this time no circuit is completed for relay 108 and no impulses are sent out. Before relay 106, which is slow to release, closes its normal contact to complete a circuit for relays 108 and 144, the subscriber 100 has again opened his switchhook contacts to again complete energizing circuits for relays 108, 106 and 107, so that relay 106 remains energized throughout the rapid open- 105 ings and closures of the switchhook contacts, and an impulse of positive polarity is trans- 110 mitted over conductor D² each time the contacts are opened. The second of these im- 115 pulses is transmitted through the left-hand contact of relay 33 and the left-hand wind- 120 ing of relay 34 to ground, to operate relay 34. A temporary locking circuit is also com- 125 pleted for relay 34 from battery through the right-hand winding and left-hand alternate contact of this relay and the contact of relay 36 to ground. A circuit is thereupon com- 130 pleted which includes the grounded inter- 135 rupter 59 and the right-hand alternate contact of relay 34, instead of the right-hand normal contact of such relay in series with

the resistance 54. Therefore, during the continued operation of relay 34, the supervisory lamp 23 will be flashed at a definite rate by the rotation of the interrupter 59. However, the opening of the left-hand normal contact of relay 34 releases relay 33, which in turn removes the signaling conductor D² from its association with the left-hand winding of relay 34 and causes the sequential 10 release of relays 35 and 36, the release of the latter relay causing the release of relay 34, thereby removing the interrupter from its relation with the circuit including the lamp 23. If, however, relay 34 is released before 15 the subscriber ceases operating his switchhook, relay 33 is again operated and thereafter relays 34, 35 and 36 are operated in the manner described. Thus, provided the openings and closings of the switchhook contacts 20 at the station G are sufficiently rapid, the relays 34 and 32 will be maintained in an operated condition so that the interrupter is continued in association with the circuit including the lamp 23. However, upon the 25 switchhook remaining in either position for a sufficient period, the relays at office X will function to produce either a steady lighting of the lamp 23 or a permanent extinguishment thereof, as the case might be.

30 The operation described above with reference to the establishment of a connection with the telephone line G for the trunk line L², and the breaking-down of such a connection, are characteristic of those taking place 35 in establishing and breaking-down a connection over any one of the trunk lines to which the signaling path P is common. The only essential differences in operation, so far as the establishment of the connections over 40 the different trunk lines is concerned, lies in the fact that different code signals are employed for the different trunk line circuits, and different sets of relays J, K and M will be operated, and the signal impulse 45 storing relays, such as relays 45, 55, 65, 75 and 85 will be operated in different combinations to determine the polarity and arrangement of the signaling impulses to be transmitted over the signaling path through 50 the sending relays associated with the storing relays. These different combinations of impulses upon being received at the distant office are distributed and cause the locking of different locking relays of the distributing 55 system, which in turn control the pyramid-selecting relays to connect the signal-receiving conductors of the various lines with the signal transmitting circuit associated with the signaling relays. While signal receiving conductors D' have been shown for 60 only 32 lines, it is obvious that any number of lines might be associated with a common signaling path by the use of additional relays such as 85, without departing from the 65 spirit of the invention.

What is claimed is:

1. In a telephone system, the combination with a plurality of trunk lines and a signaling path common thereto, of a train of relays common thereto for transmitting over 70 the signaling path code signals individual to the different trunk lines, a set of normally inert relays individual to each line for determining the code of signals for its associated line, and means controlled by a 75 change in condition of any one of the trunk lines for operating its set of relays.
2. In a telephone system, the combination with a plurality of trunk lines and a signaling path common thereto, of a train of 80 relays common thereto for transmitting over the signaling path code signals individual to the different trunk lines, a set of normally inert relays individual to each line for determining the code of signals for its 85 associated line, means controlled by any change in condition of any one of the trunk lines for operating its set of relays, and means for preventing the operation of a set of relays individual to a second line while 90 said set of relays are in operated condition.
3. In a telephone system, the combination with a plurality of trunk lines and a signaling path common thereto, of a train of relays common thereto, for transmitting over 95 the signaling path signals comprising a definite number of current impulses of positive or negative polarity, a set of relays individual to each trunk line for operating said train of relays and for controlling the 100 polarity of a certain number of the impulses in each signal, a control relay for controlling the polarity of the remaining impulses of the signal, means responsive to any change in condition on any one of said 105 trunk lines for operating its set of relays, and means responsive to certain particular changes of condition on any one of said trunk lines for operating said control relay.
4. In a telephone system, the combination with a plurality of trunk lines and a signaling path common thereto, of a train of relays common thereto, for transmitting over 110 the signaling path signals comprising a definite number of current impulses of positive 115 or negative polarity, a set of relays individual to each trunk line for operating said train of relays and for controlling the polarity of a certain number of the impulses in each signal, a control relay for controlling the polarity of the remaining impulses of the signal, means responsive to any change in condition on any one of said trunk lines for operating its set of relays, means responsive to certain particular changes of 120 condition on any one of said trunk lines for operating said control relay, and a relay individual to the impulse receiving end of said trunk line operated in response to said signal when said remaining impulses are 125 130

of one polarity and rendered inert in response to said signal when said remaining impulses are of opposite polarity.

5. In a telephone system, a train of relays, a signaling path, means for selectively operating said train of relays, a source of current of one polarity connected to a normal contact of each relay of said train, a source of current of opposite polarity connected to an alternate contact of each relay of said train, means responsive to the operation of said selective operating means for extending said signaling path to one of said contacts of the first relay of said train, a 10 pair of relays and a third relay individual to each relay of said train, means for operating one or the other of said pair of relays in accordance with the energized or inert condition of its train relay to disconnect 15 said signaling path from the source of current and to operate said third relay to extend said signaling path to one of said sources of current through a contact of the next relay of the train, said third relay 20 causing the operation of the relays asso- 25

ciated with said next train relay to successively extend said signaling path through a contact of each relay of said train.

6. In a telephone system, a plurality of transmission lines and a signaling path common thereto extending between two offices, a train of selectively operable relays, sources of current of different polarities, means responsive to the operation of said train of relays for extending said signaling path through a contact of one relay of said train to one of said sources of current, and a set of relays individual to each relay of said train operated in response to said extension of said signaling path to disconnect said path from said source of current and to extend it through a contact of another relay of said train to either of said sources of current depending upon the condition of the last mentioned relay of the train. 30 35 40 45

In witness whereof, I hereunto subscribe my name this 29th day of December A. D., 1919.

HUGH D. MACPHERSON.
